UNITED STATES PATENT OFFICE.

CHARLES H. CROWELL, OF BROOKLYN, NEW YORK.

CLOTH-TREATING PROCESS.

Application filed May 25, 1923. Serial No. 641,349.

This invention relates especially to processes of dyeing, bleaching, washing, filling, coating, gumming or otherwise treating cloth fabrics of various kinds, such as for instance, as gray goods or unbleached woven fabric of various weights, including sheetings, print cloths, tobacco cloths, cheese cloth, book binding cloth, or other still more open mesh material, such as mosquito netting or the like while minimizing or substantially preventing lateral shrinkage of the fabric. For this purpose the fabric may advantageously be laterally stretched and then passed around one or more intermeshing carrying rolls which may be in substantial peripheral contact so that the cloth may be held in tight frictional or gripping engagement with the rolls so as to be kept laterally stretched and thus prevent substantial lateral shrinkage of the fabric web while it is being treated in various ways. These carrying rolls may for this purpose have specially prepared or frictionally engaging surfaces which may be formed by knurling or otherwise roughening metal rolls or covering them with wire screening material or fabric in some cases, or other fibrous bodied or covered rolls may be used, including wood rolls which may have specially prepared or roughened surfaces, or rolls having incorporated abrasive material of various kinds may be used where special gripping engagement is desired. In some cases also endless metallic carrier surfaces such as endless belts of steel, aluminum, etc. may be used in this connection and may be supported on suitable drums or rolls so as to ensure the desired gripping engagement of the fabric with the convex surface of the carrier at least until it has been adhesively secured thereto as by adhesive filling or other treating material applied to or incorporated with the fabric. Such belt carriers may, for example, be used for first applying pasty or other aqueous adhesive treating material such as filling, coating or gumming compositions which may be applied to and spread upon the fabric while in engagement with the convex surface of a carrier belt passing over a suitable roll or drum and then when the treating material has been forced into or through the fabric sufficiently to adhesively engage the carrier belt, the carrier may pass through or into suitable drying cham-

bers or devices so that the treated fabric 55 may be dried while still in adhesive engagement with the carrier after which it may be separated or split off from the carrier which may have a smooth polished surface, if desired, or a suitably embossed or engraved 60 surface where special superficial ornamentation is to be secured on the treated fabric, such special surfaces being also used on carrier rolls in some cases where such effects are desired. 65

In some cases where thin aqueous treating material is used, such as dyeing, bleaching, or washing compositions, the carrying rolls may comprise perforated or screen surfaced carrier rolls which may be arranged in a 70 liquid treating tank more or less filled with the desired treating liquid which may penetrate the rolls so as to be applied to both sides of the web of fabric and more thoroughly and uniformly penetrate the same. 75 The fabric may, if desired, be transferred from one of these perforated carrier rolls to another by interposed transfer rolls which may have rubber or other yielding facing and be in substantial peripheral contact with 80 the carrier rolls on both sides so that the web of fabric may be kept in peripheral contact with at least one of these carrying rolls throughout its treatment at least so long as it is sufficiently wet or damp to have 85 a tendency to shrink laterally. A series of carrying rolls may be used in connection with such perforated rolls to squeeze out the surplus treating liquid from the fabric and additional pasty or other treating material may be applied to the fabric on such carrying rolls where it is desired to fill, coat, or otherwise treat the dyed, bleached or 90 washed fabric.

In many cases it is desirable to apply thick, 95 pasty filling, coating or gumming compositions to fabric webs and for this purpose a suitable applying roll or device may apply and force the treating material into the fabric while mounted on a suitable carrying 100 roll so as to prevent lateral shrinkage and after spreading or smoothing the treating material on the fabric while still on the carrying roll, the fabric may be withdrawn from this carrying roll and simultaneously wound 105 up in to a more or less tightly wound bundle roll by surface winding methods, so that this bundle roll is wound up in peripheral con-

tact with the carrier roll from which the treated fabric web is transferred. This is effective in many cases in preventing lateral shrinkage of the fabric which has relatively little tendency to shrink laterally when in a tightly wound bundle roll and in many cases this allows the more or less pasty or thick treating material to penetrate and become incorporated with the fibers of the fabric. The bundle roll of moist treated fabric may then be transferred to a suitable drying unit and forced against the periphery of a drier drum or roll or the convex surface of a metallic carrier belt by which the treated fabric may be unwound by surface winding action and transferred into frictionally gripping or adhesive engagement with the carrier surface on which it may be dried by the heat of the surface or heated air blasts or other means while being kept in peripheral contact with one or more such surfaces until it is sufficiently dry so that little or no lateral shrinkage tends to take place. It is sometimes advantageous in drying open web fabric which has not been thoroughly filled or coated to pass air through the fabric while it is supported on a perforated drier drum which may have a screen surface through which heated air may be forced or drawn so as to dry the fabric during its passage therethrough and also, if desired, be guided along the outer surface of the fabric to exert still further drying action thereon.

35 In the illustrative drawing showing in a somewhat diagrammatic way various forms of apparatus which may be used for carrying out these processes.

Fig. 1 is a vertical section through a treating or coating and winding machine.

40 Fig. 2 is a diagrammatic section through a cooperating drying apparatus which is shown on a considerably smaller scale.

Fig. 3 is a diagrammatic section through a liquid applying and treating machine which may be used in connection with such a drier, and

45 Fig. 4 is an enlarged section through one of the perforated carrier rolls.

50 In the illustrative treating apparatus shown in Fig. 1 the web of open mesh or other woven cloth or fabric 3 may be carried up over suitable guide rolls 5, 6, 7, one or more of which such as 5 is a laterally stretching roll provided with spiral or other ribs or projections to laterally stretch the fabric before it passes on to the one or more intermeshing carrier rolls such as 2 on which it is held in sufficiently gripping engagement so that lateral shrinkage is prevented. Any suitable treating material may be applied to the fabric while in such engagement with one or more carrying rolls of this general type and an applying roll such as 4 may carry up the pasty or other treating mate-

rial 20 in the tank 19 which may be removably mounted in the frame 10 of the machine so as to apply this material to the fabric 3 and, if desired, force it into and through the fabric so as to ensure the adhesive engagement between the fabric and the carrier roll 2. For this purpose it is usually desirable to have the applying roll 4 adjustable with respect to the cooperating carrier roll and the bearings 22 of this applying roll may be moved by worm adjusting gear 21 so as to accurately adjust the distance between these rolls and ensure the desired amount of material being applied to the web and forced into and through the same to the extent desired. One or more scrapers or spreaders such as 13 may be used to still further spread or force the treating material into or through the fabric, the spreader 13 being mounted in a suitable support 14 laterally movable in the guides 11 under the action of suitable adjusting screws 12 so that the desired action is secured. The treated and more or less moist or wet fabric may then be transferred to a suitable drier drum or element, or what is preferable from the practical standpoint, in many cases, the fabric may then be wound up into a more or less tightly wound bundle roll 1 by surface winding methods while still in peripheral contact with the final carrier roll 2. In this way the fabric is not at any point unsupported or free to shrink laterally. Various surface winding devices may be used to form this bundle roll which, as indicated in Fig. 1, may be wound up by the surface winding action of the carrier roll 2 and also, if desired, by a slip belt drive comprising the drive wheel 8 and the belt or sprocket chain 9 which may tend to drive or rotate the bundle roll through slipping action at a peripheral speed slightly faster than the speed of the carrier roll. In some cases it is desirable to regulate the force with which the bundle roll presses against the carrier roll and for this purpose a counter weight lever 25 connected through suitable lifting gear 23 may tend to lift the bearings 24 at each end of the bundle roll, this lifting action increasing as the bundle roll increases in diameter and weight so as to more or less equalize its downward pressure on the carrier roll. In some cases it is desirable to clean the carrier roll and remove therefrom any adherent treating material and for this purpose a moistener 15 and oscillating or other scraper 16 operated by the laterally oscillating arm 18 or otherwise, may be arranged in cooperation with the free surface of the carrier roll so as to remove undesirable material therefrom before it again engages another part of the fabric web. Of course such a machine may be used for unwinding such bundle rolls, if desired, which may be arranged above the carrier roll or at one side

55 60 65 70 75 80 85 90 95 100 105 110 115 120 125 130

135 140 145 150 155 160 165 170 175 180 185 190 195 200

of the same in which case the bundle roll may, for example, be supported in a counter weighted or counter balanced movable bearing device 26 shown as secured to the frame 5 10 at the right of Fig. 1.

In many cases it is convenient to transfer the bundle rolls of treated fabric to other treating or drying machines, especially since drum type driers cannot efficiently operate

- 10 at the same surface speed as many types of treating or applying machines. Fig. 2 shows diagrammatically a drum drier which may comprise a large metallic drum 30 six or eight feet or more in diameter which may
- 15 be heated by an internal steam space 31. This drier drum may be rotated at the desired speed so as to unwind the treated fabric 3 from the bundle roll 1 by surface winding action, the bundle roll being, if desired,
- 20 mounted for this purpose, in more or less vertical or inclined bearing slots 61, if desired, so as to have peripheral contact with the drier drum to which the damp or moist fabric web may adhere where adhesive filling or coating compositions have been applied to the fabric. This fabric after passing more or less around the drier drum may be removed therefrom by being drawn over a peripherally engaging guide roll 34 which
- 25 may be mounted in suitably inclined tightening guides 64 so as to disengage the substantially or wholly dried fabric from the drier drum and allow it to be withdrawn by the tension of the fabric to slitting, trimming or winding machines or the like. The drying of the fabric may be facilitated by air blasts and heated air from the conduit 36 may be blown or passed against the drying web of fabric on the drier drum and pass
- 30 around the circumferential blast passage 35 in the opposite direction to the fabric web so as to progressively engage the wetter or moister fabric and remove additional moisture therefrom by surface evaporation before this air enters the exhaust passage 37 so as to be withdrawn into the fan or other exhaust 38 and discharged.

In some cases, especially where more thinly liquid treating material is applied to the fabric, it is desirable to use a series of perforated or screen surfaced carrier rolls such as the three carrier or treating rolls 46, 48, 50 which may be mounted in a steam jacketed or other treating tank 55 having a steam or other heating jacket 56 more or less surrounding the same and supplied with steam or other heating fluid through the pipes 57, 58. In this way the dyeing, bleaching, washing or other treating liquid 59 may have maintained at the desired temperature and may more or less penetrate the open ended carrier rolls so as to be applied to the inner surface of the fabric as well as the outer peripheral surface of the fabric web in engagement with the carrier rolls. As

shown in Fig. 4, the carrier rolls such as 48 may for this purpose be formed with buckets such as the angle iron buckets or partitions 65 on which the inner or heavier open mesh screen 64 is supported to properly support the finer meshed outer screen or fine woven wire 63 forming a substantially smooth perforated surface over which the fabric 54 may extend. As this bucket roll rotates about its bearing 61, it carries up treating material 59 above the normal level of the liquid in the tank and allows this liquid to run or work out through the screen and fabric to more thoroughly engage the inner surface of the fabric next to the roll. 70 In order to maintain the fabric in constant peripheral contact with these screen rolls interposed yielding rubber faced transfer rolls such as 45, 47, 49 may be provided in peripheral contact therewith so that the web of fabric is transferred from one to another of these intermeshing rolls without leaving it free to shrink laterally. In this way the fabric may be transferred to other carrying or pressing rolls such as 44 mounted in the vertical part 40 of the frame 39 and cooperating, if desired, with a yielding or rubber transfer roll 43 and a metallic or other carrier or winding roll 42, these rolls being, if desired, in such close contact as to squeeze or express more or less of the treating material from the fabric where it has been immersed in treating material of this general description. If desired, also in some cases, additional filling, sizing or coating material of a somewhat more thick or pasty character may be applied to the fabric while, for instance, it is passing over the last carrier roll 42 and for this purpose an applying roll 65 having its bearings 66 adjustably or otherwise mounted in the frame may carry up and force into the fabric any suitable treating material 68 in the tank or trough 67. It is usually desirable to preliminarily stretch or extend the fabric laterally before it passes into engagement with these carrying rolls and for this purpose, as shown at the left of Fig. 3, the fabric 54 may pass over one or more guiding or stretching rolls 51, 52, 53, the last one of which, such as 51, may have spiral ribs or projections so as to stretch the web laterally just before it comes into frictionally gripping engagement with the intermeshing carrying rolls. The dyed, filled or otherwise treated fabric on the final carrying roll 42 may then, if desired, be further treated or dried, and in many cases, it is desirable to first wind up the treated fabric by surface winding methods into a bundle roll such as 41, so that the fabric is wound directly from the carrier roll 42 into this bundle roll in peripheral contact therewith, which prevents or greatly minimizes lateral shrinkage at this part of the process. Of course in the 130

case of some very open mesh fabric such as super book binding cloth, mosquito netting and the like, there is sometimes a greater tendency to shrink laterally and in such cases webs of impervious or waterproof paper or other suitable carrier webs may be wound up with the fabric into such bundle rolls as 41 so as to more surely prevent undesirable lateral shrinkage of the fabric, these interwound supporting or carrier webs being, of course, preferably removed when the fabric is dried on drier drums or devices of the general type shown in Fig. 2, and where the bundle roll 41

15 consists merely of the treated fabric, such a bundle roll may be applied directly to the periphery of the drier drum 30 and unwound by peripheral contact therewith, if desired, so as to be dried in this way.

20 This invention has been described in connection with a number of illustrative materials, proportions, conditions, arrangements and apparatus, to the details of which disclosure the invention is not of course to be limited, since what is claimed as new and what is desired to be secured by Letters Patent is set forth in the appended claims.

1. The process of treating a web of fabric which comprises passing it over a series of rotating intermeshing treating and transfer rolls in substantial peripheral contact with each other to maintain said web in frictionally gripping peripheral contact with said rolls, applying treating liquid to both sides of said fabric while on said treating rolls, applying and forcing into said fabric additional treating liquid material while said fabric is on a winding roll, and rolling the damp treated fabric into a bundle roll while in peripheral contact with said winding roll to prevent lateral shrinkage of the fabric, transferring said bundle roll into peripheral contact with a drier drum and drying the treated fabric while in peripheral contact with said drum to substantially prevent lateral shrinkage of the drying fabric.

2. The process of treating a web of fabric which comprises passing the fabric over a series of rotating intermeshing treating and transfer rolls to maintain said web in gripping peripheral contact with said rolls, applying aqueous treating material to said fabric while on said treating rolls, applying additional treating material to said fabric while on a winding roll, and drying the treated fabric to substantially prevent lateral shrinkage of the drying fabric.

3. The process of treating a web of fabric, which comprises passing the fabric over a series of rotating intermeshing treating and transfer rolls, maintaining said web in gripping peripheral contact with said rolls, applying aqueous treating material to said fabric while on said rolls, and drying the

treated fabric in peripheral contact with a winding roll whereby substantial lateral shrinkage of the drying fabric is prevented.

4. The process of treating a web of fabric which comprises laterally stretching the fabric and passing it over a series of treating carrier rolls having interposed transfer carrier rolls in substantial peripheral contact with said treating carrier rolls to maintain said web in gripping peripheral contact with said rolls, applying aqueous treating material to both sides of said fabric, rolling the damp treated fabric tightly into a bundle roll while in peripheral contact with one of said carrier rolls to prevent lateral shrinkage of the fabric, transferring said bundle roll into peripheral contact with a drier drum and drying the treated fabric while in peripheral contact with said drum to substantially prevent lateral shrinkage of the drying fabric.

5. The process of treating a web of fabric which comprises laterally stretching the fabric and passing it over a series of cooperating carrying rolls to maintain said web in frictional peripheral contact with said rolls, applying aqueous treating material to said fabric while on one of said rolls to prevent lateral shrinkage of the fabric, rolling the damp treated fabric into a bundle roll while in peripheral contact with one of said carrying rolls to prevent lateral shrinkage of the fabric, transferring said bundle roll into peripheral contact with a drier drum and drying the treated fabric while in peripheral contact with said drum to substantially prevent lateral shrinkage of the fabric.

6. The process of treating a web of fabric which comprises passing it over a series of carrying rolls to maintain said web in peripheral contact with said rolls, applying moistening treating material to said fabric while on said rolls, rolling the damp treated fabric into a bundle while in peripheral contact with one of said carrying rolls to prevent lateral shrinkage of the fabric, transferring said bundle roll into contact with a drier drum, unwinding said bundle roll and drying the treated fabric while in peripheral contact with said drum to substantially prevent lateral shrinkage of the fabric.

7. The process of filling or treating open mesh cloth fabric which comprises applying to a laterally stretched web of fabric in frictional engagement with a moving endless metallic carrier surface a coating of treating material, spreading said material and forcing the same into and through the fabric, winding the treated fabric into a tightly wound bundle roll in continuous peripheral engagement with said carrier surface to prevent lateral shrinkage while allowing said treating material to penetrate and unite with the fibers of the fabric, trans-

ferring said bundle roll into peripheral contact with an internally heated drier drum and drying the treated web while in peripheral contact with said drum and while exposed to drying air blasts to substantially prevent lateral shrinkage of the drying fabric.

8. The process of filling or treating cloth fabric which comprises applying to a laterally stretched web of fabric in frictional engagement with a moving endless carrier surface a coating of adhesive treating material, spreading said material and forcing the same into and through the fabric, winding the treated fabric into a bundle roll in continuous peripheral engagement with said carrier surface to prevent lateral shrinkage while allowing said treating material to penetrate and unite with the fibers of the fabric, transferring said bundle roll into peripheral contact with a heated drier drum and drying the treated web while in peripheral contact with said drum to substantially prevent lateral shrinkage of the drying fabric.

9. The process of treating a web of open mesh fabric which comprises laterally stretching the fabric and passing it over a rotating carrier roll to maintain said web in peripheral contact with said roll, applying liquid treating material to said fabric while on said carrier roll and rolling the damp treated fabric tightly into a bundle roll while in peripheral contact with said carrier roll to prevent lateral shrinkage of the fabric, and drying said fabric while preventing substantial lateral shrinkage thereof.

10. The process of treating a web of fabric which comprises laterally stretching the fabric and passing it over a rotating carrier roll to maintain said web in peripheral contact with said roll, applying liquid treating

material to said fabric while on said carrier roll and rolling the damp treated fabric into a bundle roll while in peripheral contact with said carrier roll to prevent lateral shrinkage of the fabric.

11. The process of treating a web of fabric which comprises laterally stretching and passing the fabric over a carrier roll, applying liquid treating material to said fabric and forcing said material into said fabric while on said carrier roll and rolling the damp treated fabric into a bundle roll while in peripheral contact with said carrier roll to prevent lateral shrinkage of the fabric.

12. The process of treating cloth fabric which comprises applying treating material to a web of fabric in frictional engagement with a rotating carrier roll, winding the treated fabric into a bundle roll in continuous peripheral engagement with said carrier roll to prevent lateral shrinkage of the fabric, transferring said bundle roll into contact with a rotating drier drum, unwinding from said bundle roll and drying the treated fabric while in peripheral contact with said drum to substantially prevent lateral shrinkage of the drying fabric.

13. The process of filling or treating cloth fabric which comprises applying to a laterally stretched web of fabric in frictional engagement with a rotating metallic surface carrier roll, treating material, forcing said material into and through the fabric, winding the treated fabric into a bundle roll while in continuous peripheral engagement with said carrier roll to prevent lateral shrinkage, transferring said bundle roll into peripheral contact with a heated rotating drier drum and drying the treated fabric while in peripheral contact with said drum to substantially prevent lateral shrinkage of the drying fabric.

CHARLES H. CROWELL.
